CLAIM

The ornamental design for a pet water dispenser, as shown and described.

DESCRIPTION

FIG. 1 is a front perspective view of a pet water dispenser showing our new design;
FIG. 2 is a front elevational view thereof;
FIG. 3 is a rear elevational view thereof;
FIG. 4 is a top plan view thereof;
FIG. 5 is a left side elevational view thereof, the right side elevational view being identical thereto; and,
FIG. 6 is a bottom plan view thereof.
